UNITED STATES PATENT OFFICE

ALFRED F. KARLSON, OF NORTH LEOMINSTER, MASSACHUSETTS, ASSIGNOR TO PARKS-CRAMER COMPANY, OF BOSTON, MASSACHUSETTS, A CORPORATION OF MASSACHUSETTS

METHOD AND APPARATUS FOR HUMIDIFYING AND COOLING THE AIR OF INCLOSURES

Application filed November 11, 1927. Serial No. 232,696.

My invention deals with a novel combination of humidifying apparatus, ventilating apparatus, and automatic regulating means for the improved humidification and cooling 5 of inclosures such as industrial factories which are influenced by uncontrollable sources of heat.

The novel purpose accomplished by my invention is the conjoined and coordinated operation of separate agencies for humidification on the one hand and for ventilation on the other under the automatic control of humidity regulators, organized to maintain the humidity required for good processing at 15 all times, and in addition to maintain the lowest possible temperature in hot weather by the continuous absorption and removal of objectionable heat from uncontrollable sources with the maximum possible rapidity.

20 My invention is especially suitable for use in connection with those common types of humidifiers that are distributed throughout the manufacturing departments of factories and that liberate a fine spray of water in the air of the room which, by evaporation, results in the presence of water vapor therein to the degree of humidity necessary for good processing. Humidifiers of such types used under the automatic control of humidity regulators 25 are in wide and common use especially in textile factories,—an extensive field to which my invention is particularly applicable.

My invention is also adapted to make use 30 of the simpler forms of ventilating means such as a plurality of relatively small power-driven fans located in window transoms. Under conditions where natural ventilation through window transoms is sufficient for the purpose I provide mechanism suitable for the 35 simultaneous opening or closing of a multiplicity of inter-connected transoms which thus become a ventilating means.

40 My invention deals not with the use of heating, humidifying and ventilating agencies which are parts of one original comprehensive design, as in central station conditioning apparatus and drying apparatus, but rather with the harnessing together of two 45 separate agencies commonly used independently of each other and for different purposes,

but united by my invention under the control of an automatic humidity regulator.

The main advantage of such a novel union of two separate agencies lies in the fact that the great majority of factories in many industries, and especially in the textile industry, 55 are already furnished with valuable humidifying equipment, including automatic regulating means that are adaptable in whole or in part to the application of my invention. 60 In all such cases the advantages of my invention are available at comparatively slight expense and investment by the simple expedient of adding to present equipment only the necessary means for producing or controlling ventilation such as I herein disclose 65 and their essential accessories.

70 My invention provides means for utilizing ordinary humidifying means of the type described under the automatic control of a humidity regulator of any suitable type to maintain the humidity of the air at a predetermined standard without recourse to ventilation or its control, under all such moderate or cool conditions of weather as do not result 75 in the accumulation of objectionable heat and temperature; also, whenever with the arrival or continuation of hot weather there occurs an accumulation of objectionable heat from uncontrollable sources and consequent objectionable temperature, my invention provides 80 for the utilization of ventilating means coordinated with the humidifying means to increase the rate of ventilation under the control of a suitable automatic humidity regulator, organized to limit the rate of ventilation thus produced to such value as will confine any subsequent fall in humidity to a predetermined limit.

85 Among the uncontrollable sources of objectionable heat, to which the atmosphere in factories is subject during periods of hot weather, may be mentioned: heat-energy dissipated by the consumption of power used 90 to drive machinery; infiltration of heat generated by the sun's rays and entering the factory through roof and side walls; sunlight entering through windows and subsequently converted into heat; and heat emanating from the bodies of human operatives. 95 100

In hot weather accumulations of objectionable heat from such uncontrollable sources unite to cause a rise in temperature which, when combined with an artificially high humidity, brings about an oppressive atmospheric condition that is a serious impairment to operative efficiency.

Provisions for maintaining reasonably low temperatures conducive to the health and industrial efficiency of operatives are no less important than provision for maintaining humidities suitable for good processing, and the removal and rejection of objectionable heat during hot weather is therefore an object of major importance.

The operation of a humidifier system absorbs heat from the air whose quantity is directly proportional to the rate of vaporization, and the removal of heat thus absorbed may be accomplished by sufficiently rapid ventilation. In hot weather, therefore, a humidifier system acquires great potential value as a cooling agency, but the cooling effect thus available cannot be realized in the presence of an insufficient rate of ventilation.

With insufficient ventilation a rise in humidity above the point for which the regulator is set actuates the regulator to interrupt the operation of the humidifiers, thus interrupting vaporization until the humidity falls sufficiently again to actuate the regulator to effect resumption of humidification. Such intermittent operation necessarily reduces the net rate of evaporation to only a fraction of the available capacity and thus impairs the available cooling effect, resulting in a temperature that can be lowered only by increasing the rate of ventilation and so increasing the "demand for moisture."

If ventilation on the other hand be excessive, vapor will be so rapidly rejected with the escaping air that humidity will fall below the desired point required for good processing and can be restored only by restricting ventilation.

That is to say, a condition of insufficient ventilation corresponds to a supply of moisture that exceeds the demand for moisture and, conversely, excessive ventilation creates a demand for moisture that exceeds the available supply.

The ideal condition for operation of a humidifier system of this type for hot weather is to maintain the humidity desired, coupled with the maximum possible cooling effect. This calls for such an adjustment of the rate of ventilation as will maintain a demand for moisture that exactly equals the total evaporative capacity of the humidifiers, thus making it possible to operate them continuously without incurring excessive humidity through insufficient ventilation or deficient humidity through excessive ventilation.

Weather that is humid as well as hot requires a relatively high rate of ventilation

since a given volume of air entering the factory from outside can absorb only a relatively small amount of vapor while being raised to the desired humidity. Conversely, weather that is dry as well as hot requires a relatively moderate rate of ventilation, since a given volume of air entering the mill can absorb a relatively large amount of vapor while being raised to the desired humidity.

The rate of ventilation, therefore, that will create the desired demand for moisture is dependent upon the outside weather and varies with it from day to day and hour to hour, making it a practical impossibility to adjust ventilation for the purposes desired by supervision or manual control. It is this constant balancing or adjustment of ventilation with evaporation for the purposes set forth that is accomplished by my invention.

It is also desirable that when cold weather approaches, ventilation should be limited to such rates as will prevent the rejection of artificial heat or of heat from natural sources that is then no longer objectionable since it may be utilized to prevent the factory from becoming too cool for comfort. While discontinuance of artificial ventilation may be manually accomplished by supervision it is desirable to accomplish it by automatic control for, in periods of moderate weather, conditions will fluctuate on the same day between extremes of heat and cold.

I have therefore made further provision of thermostatic means to effect automatic discontinuance of artificial ventilation whenever the temperature of the factory falls to any predetermined degree which it is desirable to maintain.

I use the word "inclosure" to denote a room such as one containing a factory department, that is, a room where operatives are normally present in the performance of their daily tasks, and whose efficiency would be unfavorably affected by excessive temperature. It is thereby intended to distinguish such inclosure from the compartments of drying or conditioning apparatus, which do not normally contain human operatives.

I also apply the term "water vaporizing means" to denote those types of humidifying apparatus that are so widely used in textile and other factories and which consist of spray-generating units distributed throughout such factory departments for the purpose of liberating spray directly into the air of such departments. I thus intend clearly to distinguish the class of vaporizing agencies to which my invention applies from air conditioning apparatus of the central station type, in which air is pre-conditioned as to humidity and/or temperature and subsequently supplied to factory departments or other inclosures from an outside source through ventilating ducts.

I have adopted the term "humidity regula-

5 tor" to designate a device sensitive to and actuated by variations in the moisture content of the atmosphere as commonly used for the control of humidifiers in the textile and other industries. Such devices are com-
monly of the differential thermostatic type disclosed in the preferred embodiment of
10 my invention, in which one thermostatic member is subject to the influence of the dry bulb and the other to the influence of the wet bulb temperature of the air.

15 Other devices adapted to my purpose are of the hygroscopic type with actuating elements composed of human hair, animal fibre, cross-grained wood or any other material of suitable hygroscopic property. Any such device is applicable to my purpose provided only that it be sufficiently reliable and accurate in its response to variations in humidity.

20 In the various embodiments of my invention herein disclosed I have illustrated as regulating means multi-stage regulators of the general type disclosed in Patent No. 1,284,334 granted November 12, 1918, to W. B. Hodge, since regulators of this particular type are adapted to maintain constant differential adjustments of any desired value as between two or more actuating stages with respect to any desired value of humidity.
25 Owing to this advantageous characteristic such multi-stage regulators are especially well suited to the purposes of my invention and are therefore preferred, although not essential.

30 The use of an individual humidity regulator in actuating control of the humidifying means and of a separate humidity regulator in control of the ventilating means would constitute an equivalent regulating means
35 that is equally adaptable to the purposes of my invention when maintained in properly correlated actuating adjustment as herein described. Such equivalent combinations of humidity regulating means of any suitable type may be utilized to actuate the humidifying and ventilating means for the purposes of my invention by those skilled in the art without in any way departing from its scope.

40 It is to be noted that all such devices are adapted to function in the presence of and irrespective of variations in temperature, and it is my purpose expressly to distinguish all such humidity regulators from simple wet bulb thermostats that cannot control hu-
45 midity except in the presence of a fixed and controllable temperature,—a characteristic which renders them unfit for use in connection with my invention.

50 It is also to be noted that my invention in no way contemplates reliance upon artificial heating means as such nor of thermostatic control of such means.

55 The functions of cooling and humidifying without heating which are accomplished by my invention do not require the artificial

generation of heat as a means for preserving a desired temperature or for raising the temperature and the combined elements of the apparatus that I have herein disclosed, therefore include no artificial heating means 70 or thermostatic devices for the control of such means such as are characteristic and essential parts of industrial drying apparatus.

75 Again my apparatus is required to maintain a predetermined standard of humidity at all times at whatever temperature may prevail, and, since the liberation of heat for whose removal I provide varies with the warmth of the weather and is uncontrollable, 80 the temperature that results from the cooling effect of my apparatus varies widely and is not substantially constant and controllable as in the inclosures of drying apparatus.

85 It is therefore a distinguishing characteristic of my apparatus that it operates always to reject heat from uncontrollable sources only, while maintaining substantially uniform humidity as required to facilitate processing, and is adapted for use only in inclosures 90 when cooling, and not heating, is required for the comfort and efficiency of human operatives, while industrial drying apparatus on the contrary requires the substantially constant generation of artificial heat for maintaining a relatively high temperature in inclosures where human operatives could not work continuously. In natural consequence it is clear that the heating, ventilating, humidifying and regulating elements hitherto disclosed in the drying art are not adaptable to the purpose of my invention nor are the humidifying, ventilating and regulating apparatus elements disclosed in my invention 95 either suitable or sufficient for any useful application to the practice of industrial drying.

100 It is also to be noted that the usefulness of my invention is limited to periods when the warmth of the weather and the extent of uncontrollable heat liberation are more than sufficient to maintain as high a minimum temperature as is needed either for comfort of operatives or for processing. At all other times the ventilating apparatus disclosed 105 should cease to function altogether so as to prevent waste of heat useful for comfort or processing which end is accomplished by the thermostatic means provided in one embodiment of my invention to render the ventilating means inoperative at any desired minimum temperature.

110 My apparatus therefore differs in purpose and in character from apparatus of the central station type as hitherto disclosed in that it provides for humidification and cooling 115 only by humidifying, ventilating and regulating elements, all located within the inclosure and exclusive of elements adapted for the artificial generation of heat or controlling 120 means therefor.

The elements of my novel combination of apparatus therefore comprise only a humidifying or spray-generating agency, a means or agency for accomplishing ventilation,—that is, the exhausting of air from or the supplying of fresh air into the inclosure as described,—and a humidity regulator of the class described, these three elements being organized in combination as described; and, 10 in another instance, these same elements with the addition of thermostatic means in organized combination therewith as described.

In the operation of my apparatus in warm weather, organization is such that the regulator will be actuated by rising humidity to interrupt the operation of the humidifiers, tending to cause humidity to decrease and, conjointly, to operate the ventilating means to the same effect. Conversely, the regulator 20 will be actuated by falling humidity to operate the humidifiers, tending to bring about an increase in humidity and to discontinue ventilation to the same effect.

The regulator may be provided with a 25 single actuating point or stage corresponding to a predetermined value of humidity in which case the positive actuation of the humidifiers and the negative actuation of ventilation will occur simultaneously in response to a humidity falling below the actuating level and, conversely, the negative actuation of the humidifiers and positive actuation of ventilation will occur simultaneously in response to a humidity rising above the 30 predetermined level.

Regulating means may, therefore, be provided which will operate to control the action of the humidifying means and the ventilating means simultaneously when the humidity of 40 the air of the inclosure varies from a predetermined standard of humidity, or the regulating means may be such as to cause successive operation of the humidifying means and the ventilating means when the humidity 45 of the air of the inclosure varies from said standard. The term "standard" is used herein in a broad sense as defining not only an exact desirable condition of humidity, but also such reasonable tolerance with respect 50 to said humidity as will not adversely affect processing of the material being treated in the inclosure.

While regulating means operable to cause 55 simultaneous actuation of the humidifying means and ventilating means may be employed within the broad scope of my invention, and will realize certain of its advantages, I prefer, in order to secure certain further advantage, to use regulating means providing for two actuating points or stages at 60 slightly different levels or predetermined values of humidity, and using that stage which corresponds to the lower value of humidity to actuate the ventilating means, and that stage which corresponds to the

higher value of humidity to actuate the humidifying means.

For clarification I define these two stages as marking, respectively, a deficient humidity in the case of the lower stage, an excessive 70 humidity in the case of the upper stage, and the range or interval between the two as representing a desirable humidity. By this preferred arrangement it results that so long as humidity is "desirable" the regulator 75 meanwhile actuates both the humidifying and the ventilating agencies positively and continuously and secures the advantage of utilizing the full cooling capacity of both agencies.

Should humidity fall to the level of the lower stage, becoming "deficient", regulation will cause discontinuance of ventilation, humidification meanwhile continuing. Humidity rising from a deficient condition to a desirable condition and crossing the lower limit 85 will actuate the regulator to cause resumption of ventilation. If humidity continues to rise and becomes excessive, its actuation of the regulator will discontinue humidification, permitting ventilation to continue. Humidity falling from excessive to desirable will 90 cause resumption of humidification.

In practice the interval between the two actuating stages may be slight, as little as 95 2% to 3% of relative humidity. It is to be noted that the use of two actuating points in the regulating means as just described, as compared with the use of a single actuating point, results in the simultaneous positive 100 operation of both the humidifying and ventilating agencies so long as the humidity remains desirable, that is, within the narrow range of variation corresponding to the difference between the two actuating points.

This provision therefore enables the simultaneous positive operation of both agencies during any and all periods when such simultaneous operation does not result in a deficient humidity, as would occur in extremely 105 hot dry weather, or in excessive humidity as might occur in extremely humid weather. As a result there are long periods during normal hot weather when the humidifiers will operate continuously at their full cooling capacity, with the humidity fluctuating between desirable and deficient, and automatic regulation of humidity taking place by alternate operation and interruption of ventilation 110 only.

I have adopted the term "range" of humidity in certain of the claims that follow to denote the difference or interval between the two regulator actuating points or stages, it being understood that the variation represented by this range is relatively slight, and marks a condition of humidity that is desirable.

A preferred apparatus embodying the present invention, and adapted to perform 120

the method herein described, is illustrated in the accompanying drawings, in which,

Fig. 1 is a diagrammatic horizontal sectional view through the walls of an inclosure broken into four sections, each embodying illustrations of different types of equipment which may be employed to perform the method above described;

Fig. 2 is an elevation of a pneumatic regulator of the psychrometric type showing the pneumatic connections therefrom to means for regulating the rate of moisture supply and to mechanism for controlling the rate of ventilation;

Fig. 3 is a detail view of a typical relay valve which may be employed in connection with both the moisture and ventilator controlling mechanisms;

Fig. 4 is a view, partly in vertical section, illustrating an adjustable ventilator with fluid operated means for progressively actuating the same under control of the pneumatic regulator illustrated in Fig. 2.

Fig. 5 is a detail side elevation of the ventilator-actuating mechanism illustrated in Fig. 4;

Fig. 6 is a view, similar to Fig. 2, of a multi-stage regulator having a plurality of pneumatically operable means for controlling the ventilators;

Fig. 7 is a view of one form of ventilator adapted to be controlled by the regulator or illustrated in Fig. 6; showing the ventilator in closed position, together with mechanism for successively moving it to half open and full open position, and vice versa; and,

Figs. 8 and 9 illustrate a modified form of ventilating mechanism comprising electric fans, with pneumatic controlling mechanisms respectively operable by the two-stage pneumatic devices of the regulator illustrated in Fig. 6.

Fig. 1 illustrates in horizontal section the side walls 1 and 2, and the end walls 3 and 4, of an inclosure. The illustration is broken into four sections A, B, C, D, to illustrate the different forms of ventilator-controlling and regulating apparatus embodying the invention and suitable to perform the method herein described and claimed. Such different forms of ventilation controlling and moisture regulating apparatus may be employed in the same inclosure if large enough, or may be selectively employed singly or jointly in smaller inclosures.

The apparatus diagrammatically illustrated in section "A," comprises a water supply conduit 5 having branches 6 leading to spraying devices 7 of any desired type, ventilators 8 of the transom type, a regulator 9 operable to control the ventilator-actuating mechanism 10 of the type shown in Fig. 4, and also operable through a diaphragm valve 11, or otherwise, to control the moisture supply.

The construction shown in section "B" comprises a water supply conduit 5 having branches 6 leading to spraying devices 7, a regulator 9 operable through a diaphragm valve 11, or other suitable mechanism, to control the rate of moisture supply as in section "A," but differing therefrom in that the ventilating means comprises a duct 12 having an intake or exhaust fan 13 operated from a suitable motor 14 and controlled from the regulator 9 by suitable controlling mechanism 15, as for example, a switch operable to turn on and off the motor whether the same is of the electric type, internal combustion type, or otherwise.

The apparatus illustrated in section "C" likewise comprises a water supply conduit 5 having branches 6 leading to spraying devices 7, controlled by a regulator 16 of the multi-stage type illustrated in Fig. 6, with alternately acting ventilator-actuating mechanisms 17 and 18, such as illustrated in Fig. 7.

The mechanism illustrated in section "D" also comprises a water supply conduit 5 having branches 6 leading to spraying devices 7, with a multi-stage regulator 16, such as that illustrated in Fig. 6, controlling a plurality of ventilating fans 19 and 20.

The various types of apparatus which are diagrammatically illustrated in sections A, B, C, D, will hereinafter be more fully described. It will, however, be understood that other types of ventilating moisture controlling and regulating apparatus may be employed within the scope of the invention defined in the claims.

As before stated, means are employed to ascertain or determine the moisture content or condition of humidity of the air of the inclosure and such means desirably form part of regulating apparatus for controlling the rate of moisture supply and also for controlling the rate of ventilation. A plurality of regulating devices may be provided and set to actuate the same or different ventilating devices in response to different conditions of humidity of the air of the inclosure. Preferably, however, a regulating device is employed which is adapted intermittently to control the moisture supply and the rate of ventilation in correlation to the ascertained or determined condition of humidity of the air to maintain a substantially constant desired condition of humidity. It is, of course, understood that the term "desired condition of humidity" commercially obtained is not an absolutely constant predetermined condition of humidity, but represents a narrow range approximating the ideal predetermined condition of humidity and in the present embodiments of the invention regulation of the ventilation is effected when the moisture content of the air varies with respect to the lower limit of such range of desired humidity, and that the rate of delivery of mois-

- ture to the air is varied in correlation to changes in the condition of humidity of the air with respect to the upper limit of such range of desirable humidity. Commercial 5 regulators of the type herein described have, however, reached such a degree of perfection that this range very closely approximates a constant predetermined condition of humidity.
- 10 A preferred type of intermittently operable regulator and ventilator controlling mechanism is shown in Figs. 1 to 5 of the drawings. This mechanism comprises a regulator having a casing 21 of substantially 15 rectangular form having suitable partitions therein to provide a dry bulb compartment 22 and an adjacent and parallel wet bulb compartment 23. Thermo-sensitive members, which as illustrated are in the form of 20 diaphragm motors 24 and 25, are mounted upon like walls of the compartments 22 and 23, and act upon the lower ends of levers 26 and 27 which are pivotally mounted upon brackets 28 and 29 upon the casing. The 25 upper end of the lever 26 is provided with a plurality of bosses presenting flat upper surfaces constituting valve plates and having ports 30, 31, and 32. Valves 33, 34, and 35, are slidably mounted upon the respective 30 valve plates to co-operate with the respective ports 30, 31, and 32. The valves 33, 34, are connected respectively by rods 36 and 37 with the upper end of the lever 27 which is actuated by the wet bulb thermo-sensitive member 25. The upper valve 35, which co-operates with the port 32, is adjustably connected by a rod 38 with the adjacent wall of the casing, and acts to close the port 32 only when the temperature exceeds a pre- 35 determined temperature.
- A spray head 39, which desirably is located slightly above the wet bulb compartment 23, and which may be of the "Turbo" type illustrated in Patent No. 869,945 Thompson, dis- 40 charges a spray of water into the wet bulb compartment 23. The spray thus discharged into the wet bulb compartment 32 induces a sample current of air from the enclosure, in which the regulator is situated, upwardly 45 through a screened inlet opening 40 in the lower end of the dry bulb compartment, thence through an opening 41 in the wall separating the wet and dry bulb compartments, saturates the sample current of air thus produced, and discharges it through an outlet at the lower end of the wet bulb compartment. By virtue of this construction, therefore, the dry bulb thermo-sensitive mem- 50 ber 24 is first subjected to the sample of air from the inclosure, and the wet bulb thermo-sensitive member 25 is subjected to the same current of air after it has been saturated with moisture, so that the thermo-sensitive mem- 55 bers 24 and 25 ascertain respectively the dry 60 bulb and psychrometric wet bulb temperature of the air.
- Equal variations in wet and dry bulb temperatures of the air will cause the levers 26 and 27 to move in unison and substantial 75 parallelism, while variations between the wet and dry bulb temperatures of the air will produce relative movement between the levers 26 and 27 which, acting through the links 36 and 37, will vary the relative positions of 75 the ports 30 and 31, and the valves 33 and 34. The links 36 and 37 desirably are adjustable so that the valves 33 and 34 may be set in any predetermined desired relation to the position of the ports 30 and 31 in the 80 calibration of the instrument. Such adjustment may be accomplished by screw threading the ends of the links 37 and connecting the screw threaded ends to clevises which are in turn connected to the lever 27. 85
- The relative movements of the valves and their ports are employed pneumatically to control the moisture supplying means and also the means for adjusting the ventilator. By suitable adjustment, therefore, of the 90 valves relatively to the valve ports the instrument can be set to determine the limits of the range of humidity at which the moisture supplying devices and the ventilators will be actuated. In the particular construc- 95 tion shown air under pressure is supplied from a suitable source through a pipe 42 to a branch pipe 43 which leads to relays 44 and 45 which are under the control of the regulator. A pipe 46 leads from the relay 100 100 105 110 115 120 125 130 135 140 145 150 155 160 165 170 175 180 185 190 195 200 205 210 215 220 225 230 235 240 245 250 255 260 265 270 275 280 285 290 295 300 pipe 43. A passage 61 connects the chambers 59 and 60 and a port 62 leads from the passage 61 through the restricted pipe 50 to the pipe 51 leading to the ventilator-actuating mechanism. A conical valve 63, which is backed by a light helical spring 64, normally closes the inlet end of the passage 61. A small valve rod 65 extends from the apex of the valve 63 axially through the passage 61 and enters and is seated in the conical end of a valve 66 which is slidably mounted in the casing and adapted when closed to engage and close the opposite end of the passage 61. The opposite end of the valve 66, or its stem, engages the diaphragm of the motor 57 which is mounted upon a bracket 67 secured to the casing. A helical spring 68 normally tends to force the diaphragm away from the casing so that the valve 66 is normally retained in open position, while the valve 63 is held in closed position by the spring 64, and also by the accumulation of pressure behind the valve 63.

When air is admitted to the diaphragm chamber 57 the valve 66 is forced to closed position, thereby opening the valve 63 and permitting the air under pressure entering through the pipe 43 to pass through the passage 61 and the restricted pipe 50 into the pipe 51 to actuate the ventilators. When pressure in the diaphragm chamber 57 is relieved, the helical spring 68 will withdraw the valve 66 from the end of the passage 61, thereby permitting the valve 63 to close, so that the passage of air from the pipe 43 to 50 and 51 is arrested. The pressure which has been built up in the pipe 50 is thereupon permitted to escape through a vent port 69 in the wall of the casing.

In the preferred construction shown in Fig. 2 the relay 45 through which air is supplied to the ventilator-actuating mechanism is initially controlled by the temperature valve 35 in such a manner that the ventilators cannot be opened until the air of the inclosure has reached a predetermined temperature. The relay 44, however, is under the control of the humidifier valve 33 and is normally set in such a manner as to cause delivery of spray to the air of the enclosure when such air is below a predetermined humidity. The mechanisms illustrated in Fig. 2 are shown in the position which they assume when the humidity of the inclosure is below the desired humidity, with the humidifiers of the spraying devices in operation, the ventilators closed, and the temperature of the room below that required to effect automatic opening of the ventilators.

The moisture regulating valve 33, which covers the port 30, will cause the continuance of the operation of the moisture supplying mechanism so long as the humidity is less than a predetermined maximum amount. If the humidity of the air of the inclosure in-

creases, the wet bulb temperature of the air will rise relatively to the dry bulb temperature, thereby causing relative separation of the upper ends of the levers 26 and 27. When the upper limit of the range of predetermined humidity is reached, the valve 33 will uncover the port 30 thereby releasing the air pressure in the pipe 53, thus enabling the valve spring 68 to close the relay valve 63, so that pressure in the pipe 46 will be released and the moisture controlling valve 48 will be caused to close. If the humidity decreases the upper ends of the levers will approach each other and cause the moisture control valve 33 to close the port 30 and again turn on the moisture supply.

The valve 34 is of such area and so adjusted as normally to maintain the port 31 closed when the humidity of the inclosure is below the predetermined minimum condition of humidity.

When the temperature exceeds the predetermined temperature, the dry bulb thermo-sensitive member will move the upper end of the lever 26 to the right so that the valve 35 will close the port 32; thereupon pressure will build up in the pipe 56 which will actuate the diaphragm motor 57 to open the valve 63 and permit air to flow from the pipe 43 through the restricted pipe 50 into the pipe 51. If under such conditions the humidity is below the predetermined condition of humidity, the valve 34 will not close the port 31 and the air which is supplied to the pipe 51 will be vented through the port 31 so that no pressure will be built up on the ventilator-actuating mechanism. When, however, the humidity in the inclosure increases, by reason of the continued supply of moisture thereto, until the humidity of the inclosure reaches the predetermined minimum limit of the range of humidity, the valve 34 will be moved sufficiently to close the port 31, thereby building up pressure in the pipe 51 sufficiently to open the ventilators, thereby supplying outside air to the inclosure. While the dry-bulb thermo-sensitive member of the humidity regulator is here utilized as the thermostatic means for effecting discontinuance of ventilation at and below a predetermined temperature, it is obvious that equivalent thermostatic means may be separately provided for the same purpose and, also, that the thermostatic means, of whatever type, may be omitted altogether and the discontinuance of ventilation effected manually, whenever desired, as in cool weather.

The ventilator-actuating means as a whole are desirably so constructed and organized as to effect progressive or gradual opening or closing of the ventilators by successive intermittent movements in response to the closing and opening of the port 31 by the ventilator-regulating valve 34, so that the rate of ventilation is correlated to the mois-

ture content of the air, or the condition of the air of the inclosure, this action of the regulator occurring at the lower limit of the predetermined range of desired humidity.

- 5 The interposition of restriction 50 between the relay 57 and the pipe 51 is for the desirable purpose of retarding the rise and fall of the air pressure entering the line 51 in response to the movements of the valve 34, and 10 thus assists in gradual and progressive operation of the ventilators.

The mechanism for operating the ventilator, which is illustrated in Figs. 4 and 5 of the drawings, is of the compensated step type, that is to say, operable intermittently to open or to close the ventilators step by step. As shown in Fig. 4, the ventilator is in the form of a transom 70 which is connected by a hinge 71 to a sill 72 of the transom frame and adapted to open inwardly. The upper end of the ventilator 70 is pivotally connected by a link 73 to an arm 74 of a rock shaft 75, another arm 76 of which is connected by a link 77 to the upper end 25 of a piston rod of a pressure regulator of the step compensated type such as that disclosed in Patents Nos. 1,495,079 James L. Kimball May 20, 1924, and 1,597,203 James L. Kimball August 24, 1926.

- 30 In the construction illustrated the link 77 is connected to the upper end of the piston rod 78, the opposite end of which is connected to the piston (not shown) which is reciprocably mounted in a cylinder 79. The piston 35 is actuated by fluid under pressure, admitted through a pipe 80 and discharged through a pipe 81, the flow being controlled by a compensating valve which is located in a valve casing 82. The compensating valve is actuated to admit fluid under pressure to the cylinder by a diaphragm motor which is controlled by the pressure in the pipe 51 leading 40 from the humidity regulator and is closed by a predetermined movement of the piston rod, as more fully appears in the patents to 45 Kimball above mentioned.

In this construction the valve of the compensating lever is actuated by air under pressure delivered by the action of the humidity regulator through the pipe 51 to a diaphragm motor 83 which actuates a plunger 84 which engages a knife edge 85 upon a scale beam 86 fulcrumed upon a knife edge 87. The scale beam 86 is connected through suitable 55 mechanism to the compensating valve in the casing 82 so that upon depression of one end of the scale beam by the plunger 84 the opposite end of the scale beam will be raised and the valve opened to admit air to the 60 chamber of the cylinder below the piston through a passage 88, thereby raising the piston.

The means for closing the valve upon a predetermined upward movement of the pis- 65 ton rod 78 comprises a rod 89 which is con-

nected at its upper end to the piston rod 78 and extends downwardly in parallelism with the piston rod and is connected at its lower end to a preferably adjustable controlling member 90 having a surface presenting a serrated or stepped surface 91. This stepped surface 91 engages a roller in the end of the arm 92 of a rock shaft 93 which is journaled in the frame 94 of the regulator and which rock shaft has a lever 95 fixedly connected thereto. One end of the lever 95 is connected by a coiled spring 96 to the scale beam 86, while the other end of the lever 95 is connected by a pair of links 97 (shown in dotted lines) to one end of duplicate levers 98 which are fulcrumed upon pivots, 99, on the scale beam 86. The other ends of the levers 98 are connected to a yoke 100 which in turn is pivotally connected to a yoke 101, the upper end of which is connected to the stem of the regulator controlling valve which is located in the casing 82.

In the operation of the device, therefore, the raising of the piston by pressure in the chamber of the cylinder beneath it causes the rod or link 89 to move upwardly, thereby causing the roller upon the end of the arm 92 to ride along the surface of one of the steps of the member 90. This causes the arm 92 to actuate the rock shaft 93 and the lever 95 against the tension of the spring 96, and acting through the link 97 to move the end of the lever 98 to which said link is attached upwardly, thus depressing the opposite end of the lever 98 and restoring the valve to closed position. The valve will then remain closed until admission of further pressure into the diaphragm cylinder again actuates the scale beam, whereupon the movements will be repeated and the ventilator opened step by step. The compensating valve also controls the admission of fluid under pressure to the chamber of the cylinder above the piston through a passage 102 which is shown in dotted lines in Fig. 5 as extending through the cylinder casing and communicating with an upwardly extending pipe 103 which in turn communicates with the upper end of the cylinder, so that upon release of pressure in the chamber of the diaphragm motor 83 the compensating valve will be moved downwardly intermittently to admit fluid under pressure in the chamber of the cylinder 79 above the piston, thereby moving the piston 78 downwardly and acting through the link 77 and rock shaft arms 76 and 74 and link 73 to close the ventilator.

By virtue of this construction it will be obvious that the rate of ventilation can be accurately controlled by the step by step movement of the ventilator as regulated by the action of the ventilator valve mechanism of the humidity regulator. It will be understood, however, that progressive actuation and control of ventilation as here disclosed,

while preferable for the attainment of sensitivity, is not essential to the broadest scope of the invention and that any suitable, simpler means may be used to effect the operation of ventilation, alternating between operation on the one hand and non-operation on the other.

The general operation of the apparatus in the performance of the method heretofore described is as follows:

Thermostatic adjustment is first made so that the automatic control of ventilation through the transom will not become effective until the air of the factory, or other inclosure, reaches a desired minimum temperature, say of eighty degrees. The regulator is then adjusted to maintain the desired humidity, that is, a predetermined standard of relative humidity. The apparatus then functions as follows:

In extremely cold weather, when for example the heating system of a factory is in operation, regulation of humidity will be effected by the control of the moisture supplying devices alone, the ventilator control remaining inoperative until the temperature of the inclosure reaches or exceeds the predetermined temperature established by the thermostatic adjustment.

In mild winter weather the factory will warm up during the day owing to accumulating heat from machinery and the effect of sunlight. If the heating of the factory is under thermostatic control, as is usual, artificial heat will be shut off, notwithstanding which the temperature of the air of the inclosure will continue to rise, owing to the accumulation of heat from other and uncontrollable sources, as previously described. When the said predetermined temperature is reached the ventilator control mechanism will be rendered effective and the ventilators will be opened slightly, thus resulting in evaporation of such additional moisture as will lower the temperature only to the desired minimum, with the humidity meanwhile effectively controlled.

If the cold becomes more severe, automatic ventilation will be rendered ineffective as soon as the temperature drops below said predetermined temperature. It will be noted that under these conditions no heat is allowed to escape as a result of automatic ventilation, except excess heat, while a waste of artificial heat is at all times avoided. It will thus be seen that in mild winter weather, or weather fluctuating between cool and moderate, regulation of humidity of the inclosure will at times be controlled by the regulation of the rate of moisture supply only, at times be controlled by the regulated rate of ventilation only, and at other times be controlled by the co-ordinated rates of moisture supply and of ventilation. The advantages of such control are obvious when contrasted with the disadvantages

which result without control of ventilation, for under such conditions the factory operatives will open the windows widely and indiscriminately if the factory becomes too warm, resulting in excessive local drafts and too rapid a cooling of the air of the inclosure which frequently makes it necessary to use artificial heat wastefully with the consequent wasteful expenditure of fuel.

In moderate summer weather both controls will operate co-ordinately, regulation of the rate of ventilation being employed to control the temperature of the factory at the thermostatic setting, and resulting in moderately opened transoms rather than in the maximum opening thereof.

In extremely hot weather a condition will sometimes be reached when the moisture supplying devices will be in constant operation, and for the time being the humidity control will entirely rest upon the rate of ventilation. Under these conditions the transoms will alternately open in response to rising humidity and close in response to falling humidity, adjusting the rate of ventilation to effect a substantially constant humidity, the temperature of the factory meanwhile remaining above the temperature adjustment to an extent which depends on how extremely dry and hot the outside weather may be. It should be particularly noted that under these conditions the air of the inclosure of the factory is receiving the entire benefit of the maximum cooling effect of evaporation and the resulting temperature is the lowest which it is possible to maintain by virtue of the evaporative capacity of the moisture supplying system without the humidity falling below the desired predetermined condition of humidity. It is under these last conditions that a factory which lacks such equipment suffers the most for the operatives will insist upon extravagant window openings and the resultant ventilation is so excessive that the humidity falls too low, notwithstanding which the temperature may continue to increase, as will happen when the outside air is at a higher temperature than the air inside the factory inclosure.

The controlling apparatus herein described, when employed in a humidifying system which has a sufficient evaporative capacity to cool the air of the inclosure below the outside temperature, has the great advantage, therefore, of preserving at all times an atmospheric condition which best favors processing, while at the same time insuring maintenance of the most comfortable temperature of the inclosure consistent with the maintenance of the desired condition of humidity.

In Figs. 6 and 7 a modified form of regulating apparatus is illustrated which differs from that heretofore described in that the regulator is equipped with a plurality of

ventilator controlling devices which are adapted respectively and alternately to actuate different fluid controlled motors for opening and closing the ventilators, one of the 5 actuating devices being arranged to move the ventilator from closed to half open position, and the other to move the ventilator from half open to full open position, and vice versa.

In the mechanism disclosed in Figs. 6 and 10 7 the regulator may be and preferably is the same as that illustrated in Figs. 2 and 3, with the exception that the lever 26 is provided with an additional boss 104 having a port 105 with a co-operating valve 106 connected by a link 107 to the upper end of the lever 27, the valve 106 being so arranged relatively to its port 105 that the relative movement of the levers 26 and 27 will cause the valve 106 to open or close its port in advance of the action of 15 the valve 34 to open and close its port 31. In this construction, as in the construction shown in Fig. 6, the temperature control valve 35 is so arranged as to prevent the closing of either the port 31 or 105 until the temperature of the 20 inclosure exceeds a predetermined temperature, after which the ventilator controlling valves 106 and 34 will act in succession to close the ports 104 and 31 respectively and thereby cause the operation of the respective 25 ventilator-actuating devices.

In the construction shown in Fig. 4 air under pressure is admitted through the pipe 42 and branch 43 to the moisture supply relay valve 44, and the delivery of air under pressure through the pipe 46 to the diaphragm motor 47 controlling the moisture supply valve 48 is controlled by the relative movement of the valve 33 and its port 30 in the manner heretofore described. The relative 30 movement of the temperature control valve 35 and its port 32 acts in like manner to control the diaphragm motor 57 which controls the relay 45, but in this construction the relay 45 instead of controlling directly the supply 35 of compressed air to the pipe leading to the ventilator-actuating means controls the supply of air to a pipe 108 having branches 109 and 110 leading respectively to other relays 111 and 112 which are controlled respectively 40 by the valve 34 and its co-operating port and the valve 106 and its port 104 so that so long as the temperature of the inclosure is below the predetermined temperature, the valve of the relay 45 will remain closed and no air 45 under pressure can be supplied to either of the ventilator-actuating devices. When the temperature exceeds the predetermined temperature and the valve 35 closes the port 32, pressure will be built up in the diaphragm motor 50 57 which will open the valve of the relay 45 and permit air under pressure to be supplied to both of the relays 111 and 112, and these relays will be successively operated to supply air under pressure to the respective ventilator-actuating device. Assuming, there-

fore, that the temperature of the inclosure is above the predetermined normal temperature, and the valve of the relay 45 open, relative movement of the levers 26 and 27 caused by an increase in humidity above the predetermined condition of humidity will first cause the valve 106 to close the port 104, thereby building up pressure in the pipe 113 which leads to the diaphragm motor 114 of the relay 112, thereby opening this valve and permitting air to flow from the branch 110 through the relay and through the pipe 115 to one of the ventilator-actuating devices. Upon further decrease in humidity in the air of the inclosure the valve 34 will close the port 31 thereby building up pressure in the pipe 116 which is supplied from the pipe 42 through a restricted branch 117 and will build up pressure in the diaphragm motor 118, thereby opening the valve in the relay 111 and permitting pressure to be built up in the pipe 119 leading to the other ventilator-actuating device.

A typical form of two-stage ventilator-actuating device is shown in Fig. 7. In this construction the pipe 115 leads to a diaphragm motor 120 which controls a suitable valve in a casing 121 which controls the supply of fluid under pressure, such as water, supplied through a pipe 122 and branches 123 to a pipe 124 leading to the lower chamber of a cylinder 125 having a piston, the piston rod 126 of which is connected by a pin and slot connection to one end of an actuator bar 127, so that when pressure is built up in the chamber of the cylinder 125 below the piston, the end of the bar 127 will be raised. The opposite end of the bar 127 is pivotally connected by a stud 128 to the piston rod 129 of another cylinder 130 like in all respects to cylinder 125 and which is similarly controlled by the relative movement of the humidity regulator valve 34 and its valve seat 32. However, during the movement of the piston rod 126 above described the piston rod 129 remains inactive, and the bar 127 assumes the inclined position illustrated in dotted lines in Fig. 7.

The central portion of the bar 127 is pivotally connected to the lower end of a link 131, the upper end of which link is pivotally connected to an arm 132 of a rock shaft 133, having arms 134 connected by links 135 to the upper end of the frame of transoms 136. Thus it will be obvious that when the valve 106 of the humidity regulator closes the port 104, the pressure built up in the pipe 115 will cause the actuation of the piston within the cylinder 125 to raise the bar 126 to an inclined position and thereby moving the link 131 upwardly and opening the transom approximately half-way.

Upon further decrease in humidity relative movement of the levers 26 and 27 will cause further separation of the upper ends of said levers, thereby causing the valve 34

to close its port 31. Pressure is, therefore, built up in the pipe 51 which is supplied from the pipe 42 through the restricted pipe 55, thereby building up pressure in the diaphragm motor 118, thus opening the valve of the relay 111, and supplying air through the pipe 119 to the diaphragm motor 137 which opens a valve in a casing 138 admitting fluid under pressure from the pipe 122 through the branch 139 to the pipe 140 communicating with a passage leading to the lower chamber of the cylinder 130, thereby raising the piston and piston rod 129 and causing the bar 127 to assume the upper horizontal position indicated in dot and dash lines in Fig. 7. This will again raise the link 131 and acting through the rock shaft 133 and its arms 132 and 134 and the links 135 will fully open the ventilator transom. During this movement the bar 127 will swing about its elevated end as a pivot which is maintained in elevated position by fluid under pressure in the cylinder 125.

The valves in the respective valve casings 121 and 138 also have exhaust ports communicating with opposite ends of the cylinders 125 and 130. Upon release of pressure on the diaphragm motor 120 by the opening of the port 106, the fluid under pressure in the lower end of the cylinder 125 will be exhausted through the pipe 124 and the exhaust port of the valve in the casing 121 into a waste pipe 142, and upon reduction of pressure in the diaphragm motor 120 below a predetermined amount, air under pressure will be admitted through the pipe 141 into the upper portion of the cylinder above the piston which will force the piston downwardly, thereby moving the lever 127 downwardly and rocking the ventilator toward closed position. Similarly, release of pressure in the diaphragm motor 137 will cause the exhaust port of the valve in the valve casing 138 to register with the pipe 140 and permit the fluid in the lower portion of the cylinder to flow therethrough into the waste pipe 142. Likewise reduction of pressure in the diaphragm motor 137 below a predetermined amount will open a port in the valve in the casing 138 which will admit fluid under pressure from the branch 139 of the pipe 123 into the pipe 143 from which it will pass into the upper portion of the cylinder, thereby forcing the piston and piston rod 129 downwardly, further to move the ventilator toward closed position. The operation of the cylinders 125 and 130 in closing the ventilators will be in reverse sequence to their action in opening the ventilators.

The actuation of the ventilator system in this construction is identical with that previously described in reference to Figs. 2 to 5 inclusive, except that in the construction disclosed in Figs. 6 and 7, two-stage regulation is effected instead of a multi-step regulation.

Other regulating means may be employed

as heretofore described. In Figs. 8 and 9 the ventilating means illustrated comprises electric fans 144 and 145 which are actuated respectively by motors 146 and 147, the motors being controlled through suitable connections 70 to preferably switches 148 and 149 which are actuated respectively by diaphragm motors 150 and 151 from pressure built up in the pipes 115 and 119 respectively. Any desired number of ventilator fans may be connected 75 in multiple with each of the ventilator controlling valves. It will be obvious, however, that a plurality of fans arranged in multiple and having variable speed controlling devices may be similarly actuated from the humidity regulator disclosed in Fig. 2, and the compensating regulator of the type illustrated in Figs. 5 and 6. Thus it will be apparent that the present method may be performed by various types of apparatus and 80 that the various types of apparatus particularly described herein may be employed singly, or conjointly, to regulate the condition of the atmosphere of the inclosure in the manner indicated diagrammatically in 85 sections A, B, C, and D, of Fig. 1.

While the apparatus has been herein described with particular reference to a regulator in which the humidity controlling devices have temperature controlled means automatically operable to determine the actuation of the moisture controlling mechanism and the ventilator controlling mechanism with respect to a predetermined temperature, 95 it will be understood that such mechanism is not wholly essential, and that the regulating means may be so constructed as to operate properly without the temperature controlling mechanism.

It will also be understood that whereas regulating units have been herein described adapted to control both the rate of moisture supply and the rate of ventilation, separate regulating mechanisms may be employed respectively operable to control the rate of moisture supply and the rate of ventilation.

It is also to be understood that the provision of two stages of regulator actuation corresponding to a standard of humidity having a range between an upper and a lower limit as herein disclosed is preferable for the purpose of producing serial and separate actuation of the ventilating and of the humidifying means respectively, but is not absolutely essential.

The alternative provision of a single actuating stage corresponding to a predetermined standard of humidity and adapted simultaneously to produce positive action of the humidifiers and discontinuance of ventilation 125 in response to deficient humidity on the one hand, and simultaneously to discontinue humidification and to effect ventilation positively in response to excessive humidity on the other hand, while less desirable, is a 130

practical expedient that falls within the contemplated scope of my invention.

It will further be understood that other suitable measuring or indicating devices may be employed to determine respectively the temperature and the condition of humidity, and manual regulation of the rate of moisture supply and the rate of ventilation effected in accordance with the method herein described.

It will, therefore, be obvious that the particular embodiments of the invention herein specifically set forth are of an illustrative character and are not restrictive of the meaning and scope of the following claims.

Having thus described the invention, what is claimed as new, and desired to be secured by Letters Patent, is:

1. Apparatus for maintaining relative humidity at a predetermined standard in the air of an inclosure when said air is subject to variable increases in temperature due to heat liberated therein from uncontrollable sources, comprising humidifying means acting when in operation to discharge and vaporize water within said inclosure, ventilating means operative to determine the exchange of air between the interior and exterior of said inclosure, means sensitive to and actuated by variations of the relative humidity of the air within said inclosure acting to control the operation of said humidifying means and said ventilating means, to effect discontinuance of the operation only of the humidifying means in response to humidity within the inclosure in excess of said standard, and to effect discontinuance only of said ventilating means in response to humidity within said inclosure in deficiency of said standard, to maintain said predetermined standard of humidity at all temperatures, and cool the air of said inclosure by the absorption and rejection of heat whenever the humidity of said air is at or in excess of said standard.

2. Apparatus for maintaining relative humidity at a predetermined standard in the air of an inclosure when said air is subject to variable increases in temperature due to heat liberated therein from uncontrollable sources only, comprising the construction defined in claim 1, together with means controlled by the temperature of the air within said inclosure acting when such temperature is below a predetermined degree to prevent that operation of the ventilating means which effects exchange of air between the interior and exterior of the inclosure.

3. Apparatus for maintaining relative humidity at a predetermined standard in the air of an inclosure when said air is subject to variable increases in temperature due to heat liberated therein from uncontrollable sources, comprising humidifying means acting when in operation to discharge and va-

porize water within said inclosure, ventilating means operative to determine the exchange of air between the interior and exterior of said inclosure, means sensitive to and actuated by variations of the humidity and temperature of the air within said inclosure acting to control the humidifying means and the ventilating means to maintain an exchange of air with a maximum supply of moisture when the temperature of the air of the inclosure is above a predetermined temperature and thereby produce a maximum cooling of the air of the inclosure, to effect discontinuance of the operation only of the humidifying means in response to humidity within said inclosure in excess of said predetermined standard of humidity while maintaining said air exchange and to effect discontinuance only of said exchange of air in response to humidity within said inclosure in deficiency of said standard while maintaining said maximum supply of moisture.

4. Apparatus for maintaining relative humidity at a predetermined standard in the air of an inclosure when said air is subject to variable increases in temperature due to heat liberated therein from uncontrollable sources only, comprising humidifying means acting when in operation to discharge and vaporize water within said inclosure, ventilating means operative to determine the exchange of air between the interior and exterior of said inclosure, means sensitive to and actuated by variations of the humidity of the air within said inclosure acting to control the operation of said humidifying means and said ventilating means, to restrict operation of said humidifying means only in response to humidity within said inclosure in excess of said predetermined standard and to restrict said exchange of air only in response to humidity within said inclosure in deficiency of said standard, to maintain said predetermined standard of humidity at all temperatures and to cool the air of said inclosure by the absorption and rejection of heat whenever the humidity of said air is at or in excess of said standard.

5. Apparatus for maintaining relative humidity at a predetermined standard in the air of an inclosure when said air is subject to variable increases in temperature due to heat liberated therein from uncontrollable sources only, comprising the construction defined in claim 4, together with means controlled by the temperature of the air within said inclosure and acting whenever said temperature is below a predetermined degree to prevent that operation of the ventilating means which effects exchange of air between the interior and exterior of said inclosure.

6. Apparatus for humidifying and cooling the air of an inclosure influenced by uncontrollable sources of heat comprising humidi-

fying means acting, when in operation, to discharge and vaporize water within said inclosure, ventilating means operative to determine the exchange of air between the interior 5 and exterior of said inclosure, a device sensitive to and actuated by variations of the humidity of the air within said inclosure acting to control the operation of both the humidifying means and the ventilating means to effect 10 operation of the humidifying means and to effect said exchange of air in response to humidity throughout a predetermined desirable range, to restrict operation of said humidifying means only in response to humidity 15 in excess of said range, and to restrict said exchange of air only in response to humidity in deficiency of said range to maintain a humidity within said range at all temperatures and cool the air of said inclosure 20 by the absorption and rejection of heat whenever the humidity of said air is within or in excess of said range.

7. Apparatus for humidifying and cooling the air of an inclosure influenced by uncontrollable sources of heat comprising the construction defined in claim 6, together with means controlled by the temperature of the air within said inclosure and acting, whenever the said temperature is below a predetermined degree, to prevent that operation of the ventilating means which effects exchange of air between the interior and exterior of said inclosure.

8. Apparatus for humidifying and cooling the air of an inclosure influenced by uncontrollable sources of heat comprising means for supplying moisture to the air within the inclosure by vaporization of water spray therein, ventilating means operative to determine 25 the exchange of air between the interior and exterior of the said inclosure, regulating means responsive to the humidity of the air within the inclosure, and means operable by said regulating means to maintain the rate of 30 said exchange of air only within or above a predetermined desirable range of humidity, to maintain the rate of moisture supply only within or below said predetermined range, to decrease the rate of said exchange of air in response 35 to humidity falling below said range, and to decrease the rate of moisture supply in response to humidity rising above said range to maintain a humidity within said range at all temperatures and cool the air of said inclosure by the absorption and rejection of heat whenever the humidity of said air is within or in excess of said range.

9. Apparatus for humidifying and cooling the air of an inclosure influenced by uncontrollable sources of heat comprising means for supplying moisture to the air within the inclosure by vaporization of water spray, therein, ventilating means operative to determine the exchange of air between the interior 40 and exterior of the said inclosure, regulating

means responsive to the temperature and humidity of the air within the inclosure, means operable by said regulating means above a predetermined temperature to maintain the rate of said exchange of air only within or above a predetermined desirable range of humidity, to maintain the rate of moisture supply only within or below said predetermined range, to decrease the rate of said exchange of air in response to humidity falling below said range, to decrease the rate of moisture supply in response to humidity rising above said range, and to discontinue said exchange of air below said predetermined temperature. 70

10. Apparatus for humidifying and cooling the air of an inclosure influenced by uncontrollable sources of heat comprising means for supplying moisture to the air within the inclosure by vaporization of water spray therein, ventilating means operative to determine the exchange of air between the interior and exterior of the said inclosure, regulating means responsive to the temperature and humidity of the air within the inclosure, means operable by said regulating means to limit the operation of said ventilating means to a condition of air within the said inclosure above a predetermined temperature and above or within a predetermined desirable range of humidity, and to limit the operation of said moisture-supplying means to a condition of said air within or below said predetermined range of humidity to maintain a humidity within said range at all temperatures and cool the air of said inclosure by the absorption 100 and rejection of heat whenever the humidity of said air is within or in excess of said range.

11. Apparatus for humidifying and cooling the air of an inclosure influenced by uncontrollable sources of heat comprising means for supplying moisture to the air within the inclosure by vaporization of water spray therein, ventilating means operative to determine the exchange of air between the interior and exterior of the said inclosure, regulating means responsive to the temperature and humidity of the air within the inclosure, means operable by said regulating means to limit the operation of said ventilating means to a condition of the air within the inclosure above a predetermined temperature and above a predetermined standard of humidity and to limit the operation of said moisture-supplying means to a condition of said air below said predetermined standard of humidity to maintain said standard of humidity at all temperatures and cool the air of said inclosure by the absorption and rejection of heat whenever the humidity of said air is at or above said standard and the temperature of said air is above the predetermined temperature. 110

12. Apparatus for humidifying and cooling the air of an inclosure influenced by uncontrollable sources of heat comprising means

for supplying moisture to said air by discharging and vaporizing water spray within said inclosure, ventilating means for effecting the exchange of air between the interior and exterior of said inclosure, regulating means comprising thermo-sensitive members influenced respectively by the wet and dry bulb temperatures of the air within the inclosure, means for controlling the moisture-supplying means and means for controlling the ventilating means, both actuated by the relative movement of said thermo-sensitive members and operative to increase the rate of exchange of air above a predetermined range of humidity, to increase the rate of moisture-supply below said range, and within said range to decrease the rate of air exchange in response to falling humidity and the rate of moisture-supply in response to rising humidity.

13. Apparatus for humidifying and cooling the air of an inclosure influenced by uncontrollable sources of heat comprising the construction defined in claim 12, together with means operable by the movement of said dry bulb thermo-sensitive member to render said means for controlling the ventilating means ineffective when the air within the inclosure is below a predetermined temperature.

14. Apparatus for humidifying and cooling the air of an inclosure influenced by uncontrollable sources of heat comprising means for supplying moisture to said air by discharging and vaporizing water spray within said inclosure, ventilating means for effecting the exchange of air between the interior and exterior of said inclosure, regulating means comprising thermo-sensitive members influenced respectively by the wet and dry bulb temperatures of the air within the inclosure, means controlling the moisture-supplying means and a plurality of means for controlling the ventilating means all actuated by the relative movement of said thermo-sensitive members, said plurality of means for controlling the ventilating means being successively operated to vary the rate of air exchange above a predetermined range of humidity within the inclosure, said means for controlling the moisture-supplying means being operated to increase the moisture supply below said range, and said means for controlling the ventilation and said means for controlling the moisture-supplying means being alternatively operable within said range to decrease the rate of air exchange in response to falling humidity and to decrease the rate of moisture supply in response to rising humidity.

15. Apparatus for humidifying and cooling the air of an inclosure influenced by uncontrollable sources of heat comprising the construction defined in claim 14, together with means operable by the movement of the

dry bulb thermo-sensitive member to render said plurality of means for controlling the ventilating means ineffective when the air within the inclosure is below a predetermined temperature.

16. Apparatus for humidifying and cooling the air of an inclosure influenced by uncontrollable sources of heat comprising means for supplying moisture to said air by discharging and vaporizing water spray within said inclosure, ventilating means for effecting the exchange of air between the interior and exterior of said inclosure, regulating means comprising thermo-sensitive members influenced respectively by the wet and dry bulb temperatures of the air within the inclosure, lever mechanism connected respectively to said wet and dry bulb thermo-sensitive members, a source of energy, means operable thereby for causing the actuation of said moisture-supplying means and said ventilating means, means for controlling the supply of energy respectively to said moisture-supplying means and to said ventilating means operable by the relative movement of said lever mechanisms to cause said energy to actuate said ventilating means to effect an exchange of air when the humidity of the air within the inclosure is above a predetermined range, to actuate said moisture-supplying means when the humidity of the air within the inclosure is below said predetermined range of humidity and within said predetermined range of humidity alternatively to decrease the supply of energy to said ventilating means in response to falling humidity and to discontinue said supply of energy to said moisture-supplying means in response to rising humidity.

17. Apparatus for humidifying and cooling the air of an inclosure influenced by uncontrollable sources of heat comprising the construction defined in claim 16, together with means operable by the movement of the dry bulb lever mechanism to render said means for controlling the ventilating means ineffective when the air within the inclosure is below a predetermined temperature.

In testimony whereof, I have signed my name to this specification.

ALFRED F. KARLSON.
